UNITED STATES PATENT OFFICE.

GUST CARLSON AND JOHN WIDEEN, OF BOONE, IOWA.

TABLE.

1,049,668.

Specification of Letters Patent. Patented Jan. 7, 1913.

Application filed May 3, 1911. Serial No. 624,737.

To all whom it may concern:

Be it known that we, GUST CARLSON and JOHN WIDEEN, subjects of the King of Sweden, residing at Boone, in the county of Boone and State of Iowa, have invented certain new and useful Improvements in Tables, of which the following is a specification.

This invention embodies improvements in 10 that type of tables comprising tops made in a plurality of sections whereby the table may be used as an ordinary flat top table when the top sections are peculiarly adjusted and whereby upon operation of suitable means one of the top sections may be elevated so as to form an auxiliary support quite advantageous for ordinary dining service, and affording a convenient arrangement of top members for other purposes.

20 The present invention resides particularly in the special way in which the members of the top of the table are assembled and their peculiar coöperation when in use.

25 For a full understanding of the present invention, reference is to be had to the following description and to the accompanying drawings, in which—

Figure 1 is a sectional view of a table embodying the invention showing the top sections arranged in their normal positions 30 permitting of use of the invention as an ordinary flat top table; Fig. 2 is a sectional view similar to Fig. 1, the outer movable top section being elevated and the inner top section also raised flush with the main top section; Fig. 3 is a sectional view taken on the line 3—3 of Fig. 2. Fig. 4 is a view of the locking member employed in retaining the top sections in elevated and lowered positions.

40 Throughout the following detail description and on the several figures of the drawings, similar parts are referred to by like reference characters.

45 Describing the invention specifically, a table embodying the same consists of the pedestal 1 having the central tubular standard 2 in the lower portion of which is mounted a coiled spring 3. The standard 2 carries at its upper end a frame 4 which supports the top of the table, the latter comprising a main top section 5, an inner movable top section 6 and an outer movable top section 7. The main top section 5 is provided with a large central opening and the top sections 6 and 7 are of a size and shape

conforming with that of said opening. The frame 4 has a recess 4' at its central portion beneath the opening in the main top section 5 and also corresponding in shape preferably therewith. The inner movable top section 6 is centered with respect to the section 5 by the supporting post 8 which carries the top section 7, the latter being secured in any substantial manner to the upper end of the post 8. The post 8 is of a size adapted to move freely and vertically in the hollow standard 2 of the pedestal 1, and is preferably of round form and provided with spaced annular grooves 9 and 10 between which is located an annular shoulder 11. Slidably mounted in the upper portion of the standard 2 is a horizontal locking rod 12, at the inner end of which is provided a curved locking member 13 adapted to engage either one of the grooves 9 and 10. At the outer end of the rod 12 is a handle 14 located near the outer edge of the top section 5 but below the same; convenient to be grasped for operation. A coiled spring 30 15 encircles the rod 12 and normally tends to project the locking member 13 into engagement with the post 8. The annular shoulder 11 on the post 8 tapers toward its lower end, thereby providing an inclined portion in contact with which the locking member 13 is adapted to operate. The inner movable section 6 is furthermore loosely mounted upon that portion of the post 8 between the shoulder 11 and the top section 7.

The foregoing briefly describes the construction of the invention and the operation of the means set forth is as follows: When the parts of the table are adjusted as shown in Fig. 1, the invention is used as any ordinary table would be. Should it be desired, however, to provide an auxiliary support in association with the ordinary top of the table and yet maintain the area of the top member the same as before, the operator pulls outwardly upon the rod 12 and the member 13, the latter normally engaging in the groove 9. As soon as the member 13 is disengaged from the post 8, the spring 3 previously compressed forces the parts 7 and 8 upwardly into the position shown in Fig. 2, and as the said parts approach the upper limit of their movement, the shoulder 11 engages the under side of the inner movable section 6 and raises the latter out of the recess 4', until said section 6 is flush

with the surface of the main top section 5. After the shoulder 11 has passed the locking member 13 in the upward movement of the parts 7 and 8, said member 13 may be released and the spring 15 will force the locking member into engagement with the lower groove 10 of the post 8, thereby locking positively the top sections 6 and 7 in their elevated positions. It will be apparent that to restore the top sections of the table to their original or normal positions, the locking member 13 must be withdrawn from the groove 10 and by downward pressure on the table section 7, the parts 6 and 7 may be forced downwardly against the tension of the spring 3 until locked again by the member 13 entering the groove 9. The inclined or tapered form of the shoulder 11 permits the same to be moved by the locking member 13 without necessitating that the latter be held positively out of engagement with the post 8.

Having thus described the invention, what is claimed as new is:

25 In a table of the character described, a pedestal, a single tubular standard carried thereby and forming the entire support for the top portions of the table, a horizontal frame rigidly mounted on the upper end of the tubular standard and provided upon its upper surface with a central recess, a main top section mounted upon the horizontal frame and provided with a central opening in permanent registration with the central recess of the horizontal frame, a depending surrounding flange formed upon the main top section and serving to completely conceal the horizontal frame from a lateral view,

superposed relatively vertically movable top sections adapted when placed in engagement with each other to be inserted in the registering central opening and recess and of the proper combined thickness so that the upper surface of the upper top section will be flush with the upper surface of the main top section, a depending post rigidly connected with the central portion of the upper movable top section and passing through a central opening in the lower movable top section so that the lower movable top section is vertically movable along the post, a flange fixed upon the upper portion of the post and operating in an enlarged portion of the opening of the tubular standard and adapted to engage the lower movable top section to elevate it and the end wall of said enlarged portion of the opening of the tubular standard to limit the downward movement of the post, a compressible coiled spring disposed in the lower portion of the tubular standard and engaging the lower end of the post, a reciprocatory rod passing through an opening in the depending flange of the main top section and provided at its inner end with a curved element to move into a selected one of annular grooves formed in the post to hold it in its two operative positions, and a spring to move the rod inwardly.

In testimony whereof we affix our signatures in presence of two witnesses.

GUST CARLSON.
JOHN WIDEEN.
